LIQUID FUEL SUPPLY DEVICE

Roy W. Johnson, Milwaukee, Wis.

Application December 26, 1947, Serial No. 793,975

5 Claims. (Cl. 103—25)

1

This invention relates to improvements in devices for supplying liquid fuel to burners from a source of supply remote from such burner.

In my Patent No. 2,445,069 I have shown a pumping mechanism which is adapted to deliver liquid fuel to a control device under a substantially constant hydrostatic head. The pumping mechanism utilizes a bypass associated with the pump and separate means to disconnect the pump motor if the liquid level increases over a predetermined maximum. The presence of the bypass brings in leakage problems and increases the chances of clogging, while the extra control means complicates the device.

It is one object of the present invention to provide a device for supplying liquid fuel to a burner which does not require the incorporation of bypasses and separate cutoff devices for the pump motor.

Another object of the invention is to provide a device of this type which is of simple construction, less liable to clog in operation, and which is relatively inexpensive to manufacture.

These objects are obtained by providing a continuously energized motor for operating a pump to maintain a given minimum pressure on the valve which regulates the admission of liquid to the control chamber; the operation of the motor driven pump and its delivery of liquid being controlled by an increase in the discharge pressure above a given value. Thus the delivery of liquid fuel is accomplished without resort to bypasses or separate means for disconnecting the motor from its source of power. This device can be manufactured, therefore, at a lower cost than the mechanism shown in my prior Patent No. 2,445,069.

Objects and advantages other than those above set forth will be apparent from the following description when read in connection with the accompanying drawing in which:

Fig. 1 is a view partially in section and partially in elevation of one embodiment of the present invention.

Fig. 2 is a view partially in section and partially in elevation of a second embodiment of the present invention; and

Fig. 3 is a top plan view of one element of the structure shown in Fig. 2.

The present combination generally includes a continuously energized electric motor driving a pump of the positive displacement type drawing a liquid fuel from a tank or source. The pump discharges into a conduit leading to a casing into which liquid flow is controlled by a valve biased

2

to its open position and urged to its seated position by a float shifting as the liquid level within the casing varies. A metering valve associated with the casing, controls flow of fuel to a space heater and is adjustable to different positions as the rate of combustion of the burner is to be changed. Adjustment of the metering valve may be manual or may be by automatic means thermostatically controlled from a location remote from the burner.

Referring particularly to the drawings, numeral 5 designates a conduit from a liquid fuel source or tank (not shown) at a location below and remote from the space to be heated. Such conduit is connected with a casing 6 forming a portion of a positive displacement or constant volume pump, the impeller 7 of such pump being indicated as of the sliding vane type although it will be understood that other types of positive displacement rotary impellers may be used such as shiftable vanes. A shaft 9 extends from the pump impeller 7 through a suitable packing 10 in the pump casing.

The pump casing 6 has mounted thereon a housing 13 for enclosing power means driving the pump, which means are herein shown as an electric motor 14 of the shaded pole induction type. The shaft 15 of the motor, is connected directly with the pump shaft 9 through a flexible coupling 16 herein shown as a helical spring which permits relative movement between the pump rotor and the motor rotor.

A discharge passage 20 in the pump casing 6 is connected with the inlet end of a passage 21 of a well known type of liquid level control device. It is the function of such device to supply liquid fuel to the burner at a substantially constant hydraulic head regardless of the pressure in the passages 20 and 21. The liquid level device or flow control means includes a casing 24 in which is mounted an inlet valve indicated at 25 resiliently urged in the opening direction by a spring 26. A float 27 is pivotally mounted on a bracket 28 in casing 24 and acts on the inlet valve 25 to urge such valve in closing direction as the liquid fuel within the casing rises to the desired level indicated in the drawing.

Fuel is allowed to flow by gravity from the control device to a burner (not shown) under the control of an adjustable outlet valve 33 connected with a conduit 34. The outlet valve 33 is urged in the opening direction by a spring 34 and the degree of opening of the valve is controlled by a manually adjustable cam acting by way of a lever on the outlet valve. A knob 40 is rotat-

ably mounted in the top 41 of the casing 24 and has an adjustable cam member 42 mounted on the end thereof within the casing. The cam is engageable with an ear 46 extending from a lever 47 pivoted in the casing and bearing a leaf spring 48 extending over the outlet valve for movement into and out of contact with the end of the valve upon adjustment of such valve to various positions as the knob is rotated to vary the portion of the cam in contact with the lever ear 46.

The electric motor 14 is continuously connected to the source of electric power 18 and causes the pump to supply fuel under pressure to the inlet passage 20. However, if the liquid level device is satisfied, the inlet valve 25 is closed. This causes the pressure at the delivery side of the pump to increase. At a predetermined increase the motor 14 will stall. However, the shaded pole induction motor, when stalled, draws only a little more current than when running and hence will not overheat. The motor and pump remain stalled until the liquid level device calls for more liquid.

The modification of the present invention, shown in Figs. 2 and 3, differs from the structure above described by having the pump casing 6 provided with a wall 55 which, together with a wall 56 mounted on such casing, encloses a space divided into two chambers 57 and 58 by a resilient diaphragm 59. The pump discharge passage 20 is now connected by a conduit 64 with chamber 57 and such chamber is connected with the inlet passage 21 of the valved control means. The wall 55 has mounted therein a guide 65 for push rod 66 which extends from the chamber 58 into the space enclosed by the motor housing 13. A plate 67, engageable with one end of the guide, forms one bearing surface for a helical spring 68 bearing at its other end on a plate 69 fixed on the diaphragm 59, the plate 69 providing a surface on which one end of the rod 66 may also bear. It is possible to adjust the spring 68 by screwing the guide 65 inwardly to move the plate 67 and compress the spring. The other end of the rod 66 is formed to provide a universal joint 73 supporting brake shoe 74 with brake lining 75 to bear against the edge of a disk 76 fixed on motor shaft 16.

As previously explained, the motor 14 is continuously energized and the pump 6, 7, being of the positive displacement type, discharges fuel under pressure whenever the shaft 15 rotates. So long as the flow control means requires liquid fuel for the burner, substantially all the output of the pump will be required and the pressure in the conduit 20 and inlet passage 21 remains substantially constant. However, if less fuel is required by the burner, the level of fuel in the control casing 24 rises and float 27 closes the inlet valve 25. Continued operation of the motor 15 and pump 6, 7 then builds up pressure in the pump discharge passage 20.

This pressure builds up on diaphragm 59 and compresses spring 68 until pressure plate 69 presses on the end of rod 66. Brake shoe 74—75 is then pressed against the edge of disk 76 slowing down the motor and the pump, until the required amount of fuel is delivered or until the motor 14 stalls.

It will be seen that the present device provides a power-driven pump continuously maintaining a predetermined minimum pressure on the inlet valve of flow control means which in turn maintains a given hydraulic head on the

flow control means outlet valve, except for small and relative infrequent variations in head as the quantity of fuel flowing to the burner is varied. Power is continuously applied to the pump so that the pump is ready for operation at all times and the pump-motor merely stalls when the pump discharge pressure exceeds a predetermined value. When the motor has stalled, continued energization of the motor holds the pump in substantially a given position and causes the pump to act as a check or non-return valve. The flexible coupling between the motor and pump shafts reduces the effect of stalling on the motor and may act as source of power to keep pressure on the fuel until a minimum value is again reached whereupon the pump restarts. This simple construction eliminates by-passes subject to clogging and additional power cut-off means, thus making the unit more effective and practical and lessening its cost of manufacture.

Although but two embodiments of the present invention have been illustrated and described, it will be apparent to those skilled in the art that various changes and modifications may be made therein without departing from the spirit of the invention or from the scope of the appended claims.

I claim:

1. In a device for supplying liquid fuel to a burner, a chamber, a valve controlling flow of fuel into the chamber under control of change of liquid level therein, a continuously energized shaded pole induction type electric motor, a constant volume pump driven by said motor for maintaining a supply of fuel to said valve, a brake for retarding the operation of said pump, and means responsive to pump discharge pressure above a given value for actuating the brake.

2. A device for supplying liquid fuel to a burner as claimed in claim 1, in which said means consist of a diaphragm one side of which is connected to the discharge side of said pump and the movable portion of which is connected to said brake.

3. In a device for supplying liquid fuel to a burner, a chamber, a valve controlling flow of fuel into the chamber under control of change of liquid level therein, a continuously energized motor, a pump driven by said motor for maintaining a supply of fuel to said valve, a brake for retarding the operation of said pump, and means responsive to pump discharge pressure above a given value for actuating the brake.

4. In a device for controlling liquid fuel flow to a burner, the combination with a casing having an inlet and an outlet, a valve in said inlet, a float operatively connected to said valve to open and close the valve to maintain a predetermined fuel level in the casing, of a pump connected to a source of fuel and to said inlet for delivering fuel under pressure to said inlet, a continuously energized motor, and a flexible coupling connecting said motor and said pump for storing energy upon relative rotation therebetween, the pressure rise incident to closure of said valve and continued operation of said motor being operable to stall said motor, said coupling being operable to store energy and maintain the pressure when said motor stalls.

5. In a device for controlling liquid fuel flow to a burner, the combination with a casing having an inlet and an outlet, a valve in said inlet, a float operatively connected to said valve to open and close the valve to maintain a predetermined fuel level in the casing, of a constant volume

pump connected to a source of fuel and to said inlet for delivering fuel under pressure to said inlet, a continuously energized motor, and a flexible coupling connecting said motor and said pump for storing energy upon relative rotation therebetween, the pressure rise incident to closure of said valve and continued operation of said motor being operable to stall said motor, said coupling being operable to store energy and maintain the pressure when said motor stalls.

ROY W. JOHNSON.
